United States Patent Office

Des. 234,056

Patented Jan. 7, 1975

234,056

AMPLIFIER

Shuhei Taguchi and Masaaki Miyamoto, Moriguchi,
Osaka, Japan, assignors to Matsushita Electric Industrial
Co., Ltd., Osaka, Japan

Filed Apr. 17, 1974, Ser. No. 461,765

Claims priority, application Japan Oct. 22, 1973

Term of patent 14 years

Int. Cl. D14—03

U.S. Cl. D26—14 L

FIG. 1

FIG. 2

FIG. 1 is a top, front, and right side perspective view of an amplifier showing our new design;

FIG. 2 is a bottom, rear, oblique perspective view thereof, as seen from the opposite side to that of FIG. 1.

Portions of the drawings are shaded to indicate contrast in appearance and portions are diagonally lined to indicate transparency.

We claim:

The ornamental design for an amplifier, as shown and described.
